UNITED STATES PATENT OFFICE.

HENRY B. FEBIGER, OF PHILADELPHIA, PENNSYLVANIA.

FIREARM.

No. 908,552.

Specification of Letters Patent.

Patented Jan. 5, 1909.

Application filed July 25, 1906. Serial No. 327,629.

To all whom it may concern:

Be it known that I, HENRY B. FEBIGER, a citizen of the United States, residing in the city and county of Philadelphia, State of Pennsylvania, have invented a new and useful Firearm, of which the following is a specification.

My invention relates to a new and useful fire arm and consists of means for locking the cartridge in the magazine until the proper time for feeding it upon the lifter.

It further consists of means for locking the lifter during the act of firing and until a cartridge is fed upon the same.

It further consists of other novel features of construction, all as will be hereinafter fully set forth.

Figure 1 represents a sectional view of a portion of a fire arm showing my invention in position. Fig. 2 represents a sectional view of portions of the device looking from the bottom, showing a portion of the lifter broken away. Fig. 3 represents a sectional view of portions of the device looking from the bottom, with a portion of the cartridge and the yoke in dotted lines. Fig. 4 represents, in elevation, a portion of the lifter showing the pin holding the escapement lock. Fig. 5 represents a partial sectional view and partial elevation showing the portion of the escapement lug and locking release lug with respect to the cartridge.

Similar numerals of reference indicate corresponding parts in the figures.

Referring to the drawings:—In automatic fire arms it is essential that the cartridge in the magazine be locked therein until the proper time for feeding the proper one to its position on the lifter and that this locking means be removed at the proper time in order that the cartridge can be fed from the magazine and it is further essential that the lifter for the cartridge be locked at the time of firing and until the cartridge has been fed thereonto. In the present instance I have shown a construction for accomplishing these purposes, but it will be understood that other instrumentalities may be employed for accomplishing the same results and I do not therefore desire to be limited in every instance to the exact construction herein shown and described. In the present instance I have shown a construction for accomplishing these purposes, as applied to a fire arm, similar to that covered by Letters Patent No. 797,420, granted to me August

15, 1905, and for the sake of clearness I have omitted the details of the operation of such a gun, although it will be understood that all the parts necessary to make an operative device will be fully and readily apparent from the patent above mentioned, and that while I have shown the device as applied to such a fire arm, it will be understood that I do not wish to limit myself to such mechanism as described in said Letters Patent, as I desire to apply the same to any fire arm or magazine gun and by the term "fire arm" it is to be understood that I embrace all devices such as rifles, guns, pistols, field guns or any fire arm where a construction of this character will be of advantage.

1 designates the frame of a fire arm which is adapted to be attached to a butt-stock, not shown, and to which is suitably connected all the necessary mechanism required for an operative fire arm and in Fig. 1 I have shown a portion of a trigger plate 2 in position.

3 designates a breech-block which is employed and which it will be understood is operated in the present instance in a similar manner to that described in my Letters Patent, it being understood that the same is adapted to be moved rearwardly by the force of the explosion and forwardly by the breech-block spring, not shown.

4 designates a yoke similar to that shown and described in my said Letters Patent and which is adapted to be moved rearwardly by the force of explosion and to be moved forwardly by the main recoil spring, it being seen that one of the outer sides of said yoke adjacent the inner end thereof is formed with a cam face 5.

6 designates a lifter lug which is mounted on a suitable portion of the breech-block, as described in my said Letters Patent, and which is adapted at the proper time, by the movement of the breech-block, to contact with the lifter pawl 7, which is pivotally mounted in the frame of the fire arm, and which is provided with a cam face 8 adapted to contact with the ear or projection 9 carried by or forming part of, the lifter or carrier 10. The lifter or carrier 10 is pivotally mounted in the trigger plate lugs 11 and is provided with a contact face 12 which is of suitable dimensions, as will be hereinafter understood and which is adapted to engage with a locking lug 13 carried by the breech-block, said lifter 10 having a recess or cut

away portion 14 at one side thereof, in the side adjacent the escapement.

15 designates a magazine suitably mounted in the frame of the fire arm which is provided with the follower 16 which is suitably actuated by the magazine spring 17, tending to normally force the same backwardly in order to feed the cartridges, as will be herein-after described.

18 designates an escapement which is suitably mounted in the frame of the fire arm and, in the present instance, is pivotally carried by a pin screw 19 and has a spring 20 bearing against the forward end of the said escapement in order to normally hold the forward end thereof in the path, which the cartridge must take, in its passage from the magazine to the lifter, the position being best understood from Fig. 2. The opposite end 20 of the escapement is provided with a lug 21, on the side adjacent the lifter, and which is normally in the position seen in Fig. 2, that is, removed from the path of the movement of the lifter, said lug being adapted at the 25 proper time, to be moved so that it projects over the lifter and prevents upward movement of the same, as best understood from Fig. 3, said escapement being also provided with a sear 22 and having its upper forward portion provided with a cam face 23 adapted to be engaged by the cam face 5 on the yoke 4.

24 designates an escapement lock which has a slot 25 therein in which is situated a pin guide 26 rigidly secured to the frame of 35 the gun, so that said escapement lock can move longitudinally backward and forward, as herein-after described, a spring 27 suitably connected with said lock tending to normally move the same forwardly.

28 designates a sear on said lock which is adapted at the proper time to engage with the escapement sear 22.

29 designates a release lug carried by said escapement lock which projects into the path of movement of the cartridge and is adapted to be engaged, at the proper time by the cartridge in order to return the escapement lock to its normal position and permit the return of the escapement to its normal 50 position.

30 designates a lug carried by said escapement lock and which is adapted, at the proper time, to be engaged by a pin 31, carried by the lifter, in order to prevent forward movement of the escapement lock when the lifter is elevated.

32 designates a spring suitably connected with the lifter and with a suitable stationary point and which tends to normally hold the 60 lifter in its lowermost position, to prevent any slight movement of the same when the lifter is released by the various locks and is about to be raised, to feed the cartridge into its proper position to be engaged by the breech-block in its forward movement.

The operation of the parts is as follows:— In order to charge the magazine, the breech-block is moved rearwardly manually, in any desired manner and the cartridges are passed through the opening 33 in the frame, elevating the lifter or carrier 10, which carries with it the lifter pin 31, causing the same to engage with the lug 30 on the escapement lock 24 to prevent forward movement of the same, and as the cartridges contact with the spring 75 end of the escapement, the same is forced inwardly in order to pass the cartridge into the magazine immediately springing out again in order to prevent the spring 17 from ejecting the cartridge from the magazine, it being understood that all of the cartridges are fed into the magazine in this way, the spring end of the escapement engaging with each succeeding cartridge.

In Fig. 1 I have omitted, for the sake of 85 clearness, the cartridge from the magazine, but assuming that the cartridges are in place and the follower 16 is abutting against the foremost one, it will be understood that the rearmost cartridge will be in contact with 90 the spring end of the escapement, as seen in Fig. 2, and the other parts are in position for firing, it being seen that the breech-block 3 and yoke 4 are in their foremost position, the locking lug 13 on the breech-block being in 95 engagement with the contact face 12 on the lifter, so that the latter is positively held in its depressed position. As soon as the fire arm is discharged the breech-block 3 is moved rearwardly by the force of the explosion, removing the locking lug 13 from contact with the face 12 and at the same time the yoke 4 also moves rearwardly, the cam face 5 thereon contacting with the escapement cam face 23 forcing in the forward end of said escapement against the tension of the spring 20. This movement forces out the escapement lug 21 so that the same is situated over the lifter and prevents upward movement and as the inner end of the escapement is moved outwardly the action of the lock spring 27 moves the escapement lock 24 causing the lock sear 28 to engage with the escapement sear 22, so that the said escapement is locked or held in this position, it being seen that the release lug 29 moves forwardly with the escapement lock and is situated in the path of the head of the cartridge.

As soon as the spring end of the escapement is removed, as above described, from 120 the position seen in Fig. 2, the magazine spring 17 forces out the rearmost cartridge and the same in its movement strikes the release lug 29 on the lock, as seen in Fig. 5, moving the same rearwardly carrying with it the escapement lock which thus releases the escapement and as the yoke 4 has in the meantime been moved forward by the action of the main recoil spring, the spring 20 immediately forces out the spring end of the 125 130

escapement and causes the same to engage with the head of the next succeeding cartridge in order to prevent feeding of the same. The cartridge which has been fed has 5 meanwhile reached the proper position upon the lifter and as the breech-block 3 moves forward the lug 6, as seen in dotted lines, Fig. 1, engages with the lifter pawl 7 causing the cam face 8 to ride on the ear or projection 10 on the lifter moving the same and throwing the cartridge in front of the breech-block, which carries the same forward to its position, ready for firing. As the continued forward movement of the breech-block 15 occurs, the locking lug 13 will again contact with the face 12 of the lifter lowering the same and holding it in its lowermost position, it being understood that, as soon as the release lug 29 passes the radius of the cartridge 20 head, the same will be released and will be in the position seen in Fig. 2 ready for the next cartridge.

It will be readily seen from Fig. 5 that the lug 21 is so situated, that the cartridge, by 25 reason of its shape, will pass said lug, without contacting therewith, and that the release lug 29 when in its forward position is engaged, as before stated, by the head of the cartridge and is moved rearwardly thereby 30 until overridden and released. The spring 32 tends to prevent improper movement of the lifter when the locks have been removed therefrom. The recess or cut away portion 14 on the side of the lifter allows the movement of the same without engagement with the release lug 29, as will be readily seen from Fig. 2.

Having thus described my invention, what I claim as new and desire to secure by 40 Letters Patent, is:

1. In a fire arm, a longitudinally reciprocable breech-block, a lug on said block, a lifter, pivoted means actuated by said lug for operating said lifter in order to elevate 45 the same, and means on said breech-block adapted to engage with said lifter, and lock the same in depressed position during the act of firing.

2. In a fire arm, a longitudinally reciprocable breech-block, a lug on said block, a lifter, pivoted means actuated by said lug for elevating said lifter, and a locking lug on said breech-block adapted to engage with said lifter to lock the same in its depressed 55 position during the act of firing.

3. In a fire arm, a longitudinally reciprocable breech-block, a lug on said block, a lifter adapted to be actuated by said breech block lug, a locking lug on said breech-block 60 adapted to contact with said lifter to lock the same in its depressed position during the act of firing, a pivoted cam and a second lock adapted to engage with said cam when said locking lug is removed from contact 65 with said lifter.

4. In a fire arm, a longitudinally reciprocable breech-block, a lug on said block, a lifter adapted to be actuated by said breech-block lug, a locking lug on said breech-block adapted to engage with said lifter to lock 70 the same in its depressed position during the act of firing and an escapement adapted to be actuated to lock said lifter when said locking lug is removed from contact therewith. 75

5. In a fire arm, a longitudinally reciprocable breech-block, a lug on said block, a lifter adapted to be actuated by said breech-block lug, a locking lug on said breech-block adapted to contact with said lifter and lock 80 the same in its depressed position during the act of firing, an escapement normally out of the path of movement of said lifter and means for actuating said escapement, whereby the same is moved to a position above 85 said lifter, to lock the same.

6. In a fire arm, a longitudinally reciprocable breech-block, a lifter, means on said breech-block co-acting with means for actuating said lifter, means on said breech-block 90 for locking said lifter in depressed position during the act of firing, an escapement normally out of the path of movement of said lifter and adapted to be actuated to a suitable position for locking said lifter, and means 95 for locking said escapement in this position.

7. In a fire arm, a longitudinally reciprocable breech-block, a lifter, means on said breech-block co-acting with means for actuating said lifter, means on said breech-block 100 for locking said lifter in its depressed position during the act of firing, an escapement normally out of the path of the movement of said lifter, and adapted to be actuated to a position for locking said lifter, means for 105 locking said escapement in its position, means on said locking means adapted to be engaged by a cartridge for releasing said escapement.

8. In a fire arm, a longitudinally reciprocable breech-block, a lifter, means on said breech-block co-acting with means for actuating said lifter, means on said breech-block for locking said lifter in its depressed position during the act of firing, an escapement normally out of the path of movement of said lifter, means for actuating said escapement for moving the same to position above said lifter, for locking the same, a lock adapted to engage said escapement for holding the same 110 in this position, means for moving said lock 115 to engage with said escapement, and a lug carried by said lock adapted to be engaged by a cartridge for releasing said escapement. 120

9. A fire arm, a magazine adapted to contain a cartridge, an escapement having a portion thereof normally projecting and held within the radius of the mouth of said magazine, and against which said cartridge is adapted to contact, automatic means for ac- 125 130

tuating said escapement to remove said portion whereby the cartridge can be fed from the magazine, and means suitably actuated for locking the escapement in open position.

5 10. In a fire arm, a magazine adapted to contain a cartridge, an escapement having a portion thereof projecting within the radius of the mouth of said magazine and against which said cartridge is adapted to contact 70 automatically, means for actuating said escapement to remove said portion whereby the cartridge can be fed from the magazine, means for locking the escapement in open position, and means for returning said escapement to its normal position to lock the next succeeding cartridge.

10 11. In a fire arm, a magazine adapted to receive a cartridge, an escapement having a portion thereof projecting within the radius of the opening of said magazine in order to lock the cartridge within the magazine, means for actuating said escapement for releasing the cartridge and means for locking said escapement in its open position, said 80 locking means adapted to be actuated by the cartridge to release said escapement in order to lock the succeeding cartridge.

15 12. In a fire arm, a lifter, an escapement for locking the cartridge in the magazine, a lock adapted to engage with said escapement at the proper time, and means carried by said lifter for engaging with said lock for preventing movement thereof during the elevation of the lifter.

20 13. In a fire arm, a lifter, means for locking said lifter in its depressed position during the act of firing and adapted to be released by the force of the explosion, a second lock for said lifter adapted to be automatically 95 moved into operative position by the explosion and adapted to be returned to its normal position by the cartridge which is fed from the magazine.

25 14. In a fire arm, a lifter, a lock adapted to lock the same in its depressed position during the act of firing, and adapted to be released by the force of the explosion, a second lock automatically moved into operative position by the force of the explosion, means for holding said second lock in operative position and adapted to be engaged by the cartridge from the magazine for releasing said lock.

30 15. In a fire arm, a lifter, a lock adapted to lock the same in its depressed position during the act of firing, and adapted to be released by the force of the explosion, a second lock automatically moved into operative position by the force of the explosion, means for holding said second lock in operative position and adapted to be engaged by the cartridge from the magazine for releasing said lock and means for returning said second-mentioned lock to its normal position.

35 16. In a fire arm, a lifter, means for locking

40 said lifter in its depressed position during the act of firing and adapted to be released by the force of the explosion, a cartridge stop for holding a cartridge in the magazine and adapted to be automatically actuated by the force of the explosion for permitting the feeding of a single cartridge from said magazine and means for holding said lifter in depressed position when released by said lock until said cartridge is in its proper position on said lifter.

45 17. In a fire arm, a lifter, means for locking said lifter in its depressed position during the act of firing and adapted to be released by the force of the explosion, a cartridge stop for holding a cartridge in the magazine and 80 adapted to be automatically actuated by the force of the explosion for permitting the feeding of a single cartridge from said magazine and a spring for holding said lifter in depressed position when released by said lock 85 until said cartridge is in its proper position on said lifter.

50 18. In a fire arm, a lifter and a breech-block adapted to be suitably actuated to elevate said lifter when moving forward, and 90 adapted to engage with said lifter to lock the same in its depressed position during the act of firing.

55 19. In a fire arm, a magazine adapted to contain a cartridge, an escapement automatically operated to normally hold a portion thereof within the radius of the mouth of said magazine and against which said cartridge is adapted to contact means for normally holding the same in said position, and 100 means automatically operated for permitting said escapement to remove said portion whereby the cartridge can be fed from the magazine.

60 20. In a fire arm, a magazine adapted to contain a cartridge, an escapement having a portion thereof normally projecting within the radius of the mouth of said magazine and against which said cartridge is adapted to contact, means for actuating said escapement to remove said portion, whereby the cartridge can be fed from the magazine, and means automatically operated to lock the escapement in open position.

65 21. In a fire arm, a magazine adapted to contain a cartridge, an escapement having a portion thereof normally projecting within the radius of the mouth of said magazine and against which the said cartridge is adapted to contact means for normally holding the same 115 in said position, and means automatically 120 controlling said escapement for moving the same into and out of the path of movement of the cartridge.
